UNITED STATES PATENT OFFICE.

CARL C. GROTNES, OF CHICAGO, ILLINOIS.

MACHINE FOR CORRUGATING METALLIC DRUMS.

Application filed October 18, 1924. Serial No. 744,331.

The invention pertains to the art of making metallic drums, barrels and similar articles, and has especial reference to a machine for corrugating the opposite ends of cylinders employed in the construction of such articles, for the purpose of lending strength and rigidity thereto.

The object of my invention generally stated is to produce a machine of the character indicated which is capable of effectually performing the corrugating operation with a high rate of production and with a relatively small expenditure of time and effort on the part of the operator, so that the cost of the operation shall be reduced to a minimum.

More specifically, it is an object of the invention to produce an automatically operating machine capable of corrugating opposite ends of a cylinder simultaneously, and so constructed and arranged as to permit the insertion and removal of the cylinder by simply rolling it into and out of position. To this end a feature of primary importance is the mounting of the forming rolls for relative swinging movement so that one of each pair of rolls is capable of swinging into and out of the end of the cylinder without necessitating any longitudinal movement of the latter.

Another object is to provide a construction of ample strength and rigidity to operate upon sheet metal of relatively heavy gage without undue wear and tear upon the parts and without the use of equipment complicated in character and not only expensive but consuming a great deal of floor space. In carrying out this object, my invention contemplates the provision of a low elongated base or bed rendering the insertion and removal of the work extremely facile, and providing at opposite ends of the bed pivoted upstanding arms, each carrying one of two forming rolls of which the other roll is mounted on a fixed horizontal axis, and in further providing power actuated cam means for moving said arms, the latter constituting levers of the third class for effecting the positive movement of the swinging roll into operative engagement with the work placed upon the other roll.

A machine of preferred construction and arrangement is shown in the accompanying drawings forming part hereof and will presently be described in detail. It is contemplated, however, that various changes in the

construction and arrangement set forth may be made by those skilled in the art without departing from the spirit and scope of the invention as expressed in the appended claims.

Figure 1 of the drawings is a side elevational view of my improved drum corrugator.

Fig. 2 is a plan view of the machine showing the drive shaft broken off.

Fig. 3 is a horizontal plan section taken approximately in the plane of line 3-3 of Fig. 5.

Fig. 4 is a fragmentary longitudinal sectional view approximately centrally of the machine but taken through one end thereof only.

Fig. 5 is a transverse sectional view taken approximately in the plane of line 5-5 of Fig. 4.

Fig. 6 is a fragmentary front elevational view of the right hand end of the machine with the movable roll swung upwardly into inoperative position.

Fig. 7 is a fragmentary horizontal section taken in the plane of line 7-7 of Fig. 5 to show a detail of construction.

The machine comprises an elongated base or bed 10 supported upon relatively short legs so that the operating mechanism mounted on the bed shall be positioned relatively low for convenience in inserting and removing the work to and from the machine and in attending to the operation thereof. At opposite ends of the bed are mounted in opposed relation two heads generally designated 11 and 11'. Each comprises a horizontal or stationary section 12 and a normally upright section 13 in the form of a rocker arm or lever pivoted to swing on a horizontal axis relative to the horizontal section 12. The latter in each instance rotatably supports the lower one of two corrugating rolls 14 and 15, and the lever arm 100 rotatably supports the upper one of said rolls. Each of the heads moreover embodies a cam 16 mounted in the lower or horizontal section and arranged to operate upon the lever arm to move the forming roll carried thereby into operative engagement with the work which is positioned upon the lower roll 14. The arrangement is such that the lever arms 13 of the heads are swung in the operation of their respective cams 16 from the position indicated in Fig. 6 to that shown in Fig. 1, it being observed that when the

105

110

upper rolls are in the position shown in Fig. 6 they clear the opposite ends of the cylinder to be operated upon, as the latter is rolled into position upon the lower rolls.

5 Referring now to Fig. 3, the bed 10 comprises opposite side members or rails 17 connected together by end pieces 18 and 19 and an intermediate cross piece 20. Extending longitudinally of the bed and mounted in 10 the end piece 18 and the cross piece 20 is a shaft 21, suitable bearings 22 and 23 being provided for this purpose. Said shaft extends a substantial distance to the right of the bearing 23 and has a spur gear 24 splined 15 thereon, between a pair of opposed bearing members 25 depending from the lower section of the head 11'. Said gear 24 is arranged to mesh with a similar gear 26 to drive the lower forming roll of this head. 20 The shaft 21 also carries a gear 27, located between the bearings 22 and 23 and adjacent a depending bearing member 25^a. Said gear is arranged to mesh with a similar gear 28 for driving the lower roll of the other head 11.

25 The shaft 21 is constantly driven from a drive shaft 29 (Fig. 3) suitably mounted in bearings 30 and 31 upon the rear rail 17 of the bed and extending parallel to the shaft 30 21. The connection between the two shafts consists of a spur gear 32 on the left hand end of the shaft 21 meshing with a pinion 33 on the shaft 29; and the latter shaft is arranged to be connected with a suitable source 35 of power indicated in the present instance by a pulley 34. A clutch 35 (Fig. 1) is interposed between said pulley and the shaft 29 which clutch is arranged to be actuated by means of a lever 36 which is pivoted between its ends on a bracket 37 and connected by means of a link 38 with a bell-crank lever 40 mounted at the left hand end of the base on a shaft 41. One arm of said lever constitutes a treadle 42 whereby the clutch may 45 be operated by the foot of the operator.

50 Referring now to Figs. 4 and 5, the head 11 is mounted upon the upper side of the base 10 at the left hand end thereof so as to be capable of longitudinal adjustment for facilitating the assembling operation. Thus the lower horizontal section 12 of the head comprises a plate 43, the opposite edges of which interengage with the upper edges of the side rails of the frame in a well known manner. Rising from the inner end of said plate, in spaced longitudinal relation, are a pair of bearing brackets 44 and 45 in which is journaled a stud shaft 46 having keyed thereon the lower forming roll 14. Said shaft 46 extends outwardly beyond the bracket 44 and has rigid therewith the spur gear 28, the lower portion of which protrudes into a slot 47 in the plate 43 for engagement with the spur gear 27 on the shaft 21.

55 From the opposite side edges of the plate 43 rise upright members 49 which are cut away to receive bearing blocks 50 which with said members 49, provide journal bearings in which are mounted trunnions 51 formed integral with the lower end of the lever arm 13 and projecting from its forward and rear edges. Said lever arm is bifurcated at its lower end so as to form a recess 52 for receiving the spur gear 28. At its upper end 60 the lever arm is constructed to provide a flat support upon which is adjustably mounted a U-shaped frame 53 in the opposite sides of which are journaled the opposite ends of a shaft 54 carrying the upper forming roll 59.

65 The rolls 14 and 15 are herein rigidly secured upon their shafts 46 and 54, and the construction is such that the ends of the shafts are capable of a limited longitudinal movement in their bearings so as to permit the two sets of rolls at opposite ends of the drum to move toward each other during the formation of the corrugations. The reason for such movement of the rolls is that the 70 drum becomes shorter as the corrugations are formed and more especially when they are formed outwardly or upon the exterior of the drum. The direction of this movement is toward the right (Fig. 1), and to restore the rolls to their initial positions at the completion of the forming operation, I provide in the present instance a leaf spring 75 for each shaft, bearing against the inner ends thereof. The frame 53 may be mounted for adjustment on the upper end of the lever arm 13 in any suitable way. Herein the frame is secured at opposite side edges of the arm (Fig. 7) by means of a pair of plates 56 and bolts 57 so as to be adjustable vertically relative to the arm. A pair of stop screws 58 are mounted in the upper end of the arm and adapted to engage with the upper end of the yoke to receive the upward strain during the forming operation.

80 Upon the opposite side of the rocker arm 13 there are formed a pair of spaced members 59 (Figs. 2 and 4) in which are mounted the opposite ends of a pin 60. Carried between the members 59 is a roller 61 located substantially midway between the upper and lower ends of the arm. This roller is normally held in engagement with the cam 16 by means of a weight 62 connected with the arm by a cable 63 passing over an idler 63^a on the cam shaft. The arrangement is such that when the arm is drawn back into its inclined position (Fig. 6) the weight 62 rests upon the floor beneath the bed. This prevents any jarring or shock such as might be caused were a spring employed.

85 The cam 16 of the head 11 is keyed on a transverse shaft 64 the opposite ends of which are mounted in bearing boxes 65 entering notches 66 in the upright side mem-

bers 49 of the table 43. Upon the upper edge of each of these side members 49 is secured a cap 67 for retaining the boxes 50 and 65 in place. The bearing box 65 may be 5 of any suitable or preferred construction. Preferably I provide for the adjustment of the shaft 64 to vary the position of the cam relative to the arm 13 and this is accomplished by a pair of wedges 68 acting on opposite sides of the bearing box and arranged to be actuated by adjusting screws 69 so as to vary the positions of the boxes and hence of the shaft relative to the notches 66. By 10 this construction it is possible readily to adjust the positions of the rolls so that as they move into position to complete the forming operation they occupy a true parallel relation.

While I have above described the construction of one of the heads only, it will be apparent that the two heads are similar in all substantial respects so that such description will suffice for both. It need only be pointed out that the head 11' is mounted upon the 20 bed for longitudinal adjustment so that the machine may accommodate drums of different lengths. The vertical adjustment of the upper rolls 15 upon the rocker arms 13 permits of an adjustment to accommodate different thicknesses of metal. The means which I provide for adjusting the head 11' on the bed comprises in the present instance a screw 70 mounted in a bracket 71 in the extreme right hand end of the machine and held against longitudinal movement therein by collars 72. The screw engages a nut 73 depending from the head between the side rails of the bed.

The means for actuating the cams 16 comprises (Figs. 1 to 5) a shaft 74 (Fig. 3) mounted at the rear side of the machine upon a pair of rearwardly and downwardly extending bracket arms 75 providing journal bearings for the shaft. Said arms also provide housings 76 enclosing worms 77 on the shaft 74, and are secured as by means of bolts 78 to the respective heads 11 and 11'. The worms are splined upon the shaft 74 so as to permit of their movement longitudinally thereof with the heads 11 and 11' in the adjustment of the latter on the base. The shaft 74 is driven in the present instance from the shaft 29 by means of a spur gear 79 meshing with the pinion 33 at the left hand end of the machine; and the worm gears 77 mesh with worm wheels 80 which are mounted on rearward extensions of the cam shafts 64. It will thus be apparent that I provide a common driving means for the two heads which not only imparts rotation to the lower forming rolls but effects the desired swinging movement of the upper rolls.

To support the cylinders during the forming operation, I provide on each of the heads

a pair of transversely or laterally spaced rolls 81 suitably journaled in bearing heads 82 which are mounted upon laterally extending supporting members 83 rigid with the horizontal section of the head. Said 70 bearing heads 82 are adjustable laterally or transversely toward and from the axis of the stationary roll, being for this purpose adjustably secured to the supports 83 by means of bolts 84. It will be apparent that 75 by thus adjusting the rollers 81 toward and from the stationary forming rolls, they may be readily adapted to support drums of varying diameters. As shown clearly in Fig. 2 each of the rollers has a flanged head 80 85 against which the end of the drum is adapted slidably to engage.

In operation, it is only necessary in inserting a drum in position in the machine to roll it upon the rolls 81 until it rests upon 85 both the front and rear rollers and the lower forming roll. When thus inserting a cylinder, it will be understood, the lever arms 13 are swung upwardly into the position shown in Fig. 6 in which the upper forming rolls 90 15 clear the opposite ends of the cylinder. A depression of the treadle 42 thereupon drives the lower forming rolls and at the same time swings the lever arms downwardly and inwardly into the opposite ends 95 of the cylinder. As will be apparent from Fig. 4 the cams 16 are so shaped as to swing the arms at a relatively high rate of speed until they approach the work, and that thereupon the cams operate to move the arms slowly and carry the rolls 15 positively and with great force into engagement with the work upon the lower rolls 14. The forming operation having been completed, the rollers 100 61 immediately disengage from the cams 16 105 and the weights 62 operate to withdraw the rolls 15 instantly from within the ends of the cylinder. It is thus possible during the continued rotation of the cams to the 110 position in which they again engage the 115 rollers 61 for the operator to remove the completed cylinder and to replace it with a new one. Thus the operation may be performed at relatively high speed to bring about a high rate of production.

I claim as my invention:

1. A machine of the character described comprising, in combination, an elongated base frame, a pair of heads mounted on the frame in longitudinal spaced relation, each of said heads having a forming roll rotatably mounted on a fixed axis, a second forming roll mounted to rotate on an axis movable toward and from the axis of the stationary roll, a lever supporting said movable roll, and cam means arranged to operate said lever.

2. A machine of the character described comprising, in combination, a forming roll mounted to turn on a stationary axis, a 130

- 2 second forming roll mounted for swinging movement from a position parallel to the stationary roll into a position approximately at right angles to the stationary roll, and power-driven means for swinging the movable roll to effect its rapid approach toward the stationary roll preliminary to the final movement at relatively slow speed during the forming operation.
- 10 3. A machine of the character described comprising a base, a head mounted on the base, a forming roll mounted to turn on a horizontal axis in the head, a lever mounted for swinging movement in the head and having a second forming roll mounted thereon, said lever being swingable to carry said movable roll from a position beyond one end of the stationary roll into a position directly thereover and vice versa, and means including a cam for swinging said lever.
- 15 4. A machine of the character described having a forming roll mounted to turn on a fixed horizontal axis, a lever arm mounted to swing on a horizontal axis extending in a direction perpendicular to the axis of said forming roll, a second forming roll mounted to turn on said lever into a position parallel to the axis of the first roll, and means for actuating said lever comprising a cam operating to swing said lever at a relatively high rate of speed from its normal inoperative position to a position such that the movable roll approaches the other roll and then at a slow or working speed to perform the forming operation.
- 20 5. A machine of the character described having a pair of heads mounted in spaced relation and each having a forming roll mounted therein on a fixed horizontal axis, means on opposite sides of each of said forming rolls to retain a cylinder in position upon said forming rolls, a second pair of forming rolls mounted for swinging movement from a position clear of the ends of the cylinder placed on the first mentioned rolls into positions in the opposite ends of the cylinder and over said first mentioned rolls, and means operating to move said movable rolls into the ends of the cylinder first at a high rate of speed through the major portion of the movement and then at a low or working speed to produce the forming operation.
- 25 6. A machine of the character described having a pair of forming rolls mounted for relative swinging movement from a normal position in which the axes of the rolls are approximately at right angles to each other to an operative position in which the axes of the rolls are approximately parallel, and means for effecting such relative swinging movement adapted initially to operate at a relatively high speed while the rolls move toward their operative relation and then at a low speed during the forming operation.
- 30 7. A machine of the character described having a pair of forming rolls mounted for relative swinging movement from a normal position in which the axes of the rolls are approximately at right angles to each other to an operative position in which the axes of the rolls are approximately parallel, and means for effecting such relative swinging movement adapted initially to operate at a relatively high speed while the rolls move toward their operative relation, then at a low speed during the forming operation, and finally to effect the return of the rolls to their normal inoperative position at a high speed.
- 35 8. A machine of the character described having two forming rolls mounted for relative swinging movement, means tending to restrain such relative swinging movement, and a cam for effecting such movement at a high speed during the major portion of the movement from a normally inoperative position toward a working position, then at a low speed during the forming operation, and finally to permit a reverse movement between the rolls at a high speed by said restraining means.
- 40 9. A machine of the character described comprising a forming roll, means rotatably supporting said roll on a fixed axis, a lever arm mounted on said supporting means for swinging movement from an inclined position to an upright position and vice versa, a second forming roll carried by said lever arm, and cam means for operating said lever arm to carry the second roll into operative association with the first roll, said cam means being adapted to swing said lever arm from its inclined position to an upright position at a high rate of speed and then to continue the movement of the arm at a slow speed to accomplish the forming operation.
- 45 10. A machine of the class described having a support, a forming roll mounted on said support to turn on a longitudinal axis, a lever arm mounted to turn on a transverse horizontal axis located at one end of said forming roll, said lever arm having a second forming roll thereon and being movable from an inclined position to an upright position to carry said roll from an inoperative position into operative relation with the first mentioned roll, and means for swinging said lever arm comprising a cam mounted on a transverse axis spaced from the axis of the arm in a direction away from the forming rolls and adapted operatively to engage with said arm to move it first at a high speed from its said inclined position to its upright position and then at a low speed to accomplish the forming operation, the axes of the rolls in the upright position of the lever arm being substantially parallel.
- 50 11. A machine of the class described hav-

ing a support, a forming roll mounted on said support to turn on a longitudinal axis, a lever arm mounted to turn on a transverse horizontal axis located at one end of said forming roll, said lever arm having a second forming roll thereon and being movable from an inclined position to an upright position to carry its roll from an inoperative position into operative relation with the first mentioned roll, means for swinging said roll comprising a cam mounted on a transverse axis spaced from the axis of the arm in a direction away from the forming rolls and adapted operatively to engage with said arm to move it first at a high speed from its said inclined position to its upright position and then at a low speed to accomplish the forming operation, the axis of the rolls in the upright position of the arm being substantially parallel, and a weight operating to return the arm to its inclined position after the completion of the forming operation.

12. A machine of the character described comprising a pair of forming rolls one of which is mounted to rotate on a fixed axis and the other of which is mounted to swing from a position in which its axis is substantially parallel to the axis of the other roll into a position approximately at right angles to said axis of the other roll and vice versa, and means for swinging the movable roll from the last mentioned position into such parallel relation to the stationary roll comprising a cam operating to move the movable roll initially and during a major portion of its movement at a high rate of speed and finally at a low or working speed.

13. A machine of the character described having a forming roll mounted to turn on a stationary axis and a second forming roll mounted to turn on a swinging axis, a cam mounted on an axis extending transversely to the axis of the rolls and spaced a substantial distance from one end of the stationary roll, and means for swingably supporting the movable roll comprising a lever fulcrumed on a transverse axis located between the stationary roll and the axis of said cam and a roller on said lever adapted to be engaged by said cam, the arrangement being such that when the highest point on the cam engages the roller the two forming rolls are disposed in approximately parallel relation.

14. A machine of the character described comprising a relatively flat support, a forming roll mounted on a longitudinal axis substantially centrally of said support near one end thereof, means for rotating said roll including a gear train, said support having an opening through which said gear train operates, a movable forming roll, and a lever arm supporting the movable roll having a bifurcated lower end arranged to straddle a

portion of said gear train and having trunnions mounted in said support at opposite sides thereof.

15. A machine of the character described having a head comprising a relatively flat support with upright members at opposite side edges thereof, a forming roll mounted on an axis extending longitudinally of the support near one end thereof, a lever journaled in said upright members on the support and having a movable forming roll mounted thereon, and a cam having a shaft also mounted in said upright members, said cam being adapted operatively to engage said lever to move the forming roll thereon into engagement with the roll on said support.

16. A machine of the character described having a head comprising a relatively flat support with upright members at opposite side edges thereof, a forming roll mounted on an axis extending longitudinally of the support near one end thereof, a lever journaled on said support and having a movable forming roll mounted thereon and a cam having a shaft mounted in said upright side members, said cam being adapted operatively to engage said lever to move the forming roll thereon into engagement with the roll on said support, said shaft being mounted for adjustment toward and from the axis of said arm.

17. A machine of the character described having a pair of forming rolls mounted for relative swinging movement, one of said rolls having a supporting member mounted for swinging movement on a fixed axis extending transversely of the axis of the forming roll carried thereby and having a roll-supporting member mounted for adjustment longitudinally of the member whereby to vary the distance between the rolls when in parallel relation.

18. In a machine of the character described, the combination of a forming roll mounted to turn on a fixed axis, a movable roll, a support for the movable roll adapted to carry it into and out of parallel relation to the stationary roll, power-driven means for actuating said support through a fixed arc of movement, and means for adjusting the movable roll on its support to vary the distance between the rolls when in parallel relation.

19. A machine of the character described comprising a support having a forming roll mounted to turn on a fixed axis, a second forming roll mounted for movement toward and from the first forming roll, said second forming roll having a support in which it is journaled so as to be capable of limited longitudinal movement therein, and means yieldably restraining such longitudinal movement of the movable roll.

20. A machine of the character described

- comprising an elongated bed, a head at each end of the bed, means carried by adjacent ends of the two heads for rotatably supporting a cylinder in position thereon, a
- 5 forming roll mounted in each head adapted to contact with the under side of the cylinder when thus supported, each of said heads having a second forming roll mounted for swinging movement into and out of the ends
- 10 of the cylinder, and means carried by the respective heads for swinging the movable rolls.
21. A machine of the character described comprising an elongated bed, a head at each end of the bed, means carried by adjacent ends of the two heads for rotatably supporting a cylinder in position thereon including a forming roll mounted in each head and adapted to contact with the under side of the cylinder, each of said heads having a second forming roll mounted for swinging movement into and out of the ends of the cylinder, means carried by the respective heads for swinging the movable rolls, and
- 25 a drive mechanism mounted in the bed and operatively connected with the stationary rolls of each head to rotate them.
22. A machine of the character described comprising an elongated bed, a head at each end of the bed, a forming roll mounted in each head adapted to contact with the under side of the cylinder, each of said heads having a second forming roll mounted for swinging movement into and out of the ends of the cylinder, and means for swinging the movable rolls, comprising a cam mounted in each head, a driven shaft mounted in the base, and a worm gearing connection between the shaft and the respective cams.
- 40 23. A machine of the character described comprising a base, a pair of heads mounted on the base, a pair of forming rolls carried by each head, one of said heads being adjustable longitudinally of the base, a pair of shafts extending longitudinally of the base and arranged to be driven, means connecting one of said shafts with one of each pair of forming rolls adapted to permit of the adjustment of one of said heads, cam means for actuating the movable roll of each head, and means operatively connecting the other one of said shafts with the respective cam means also adapted to permit of the longitudinal adjustment of one of said heads.
- 55 24. A machine of the character described having a base, a pair of heads mounted at opposite ends of the base, forming rolls carried by each head and mounted to turn on a fixed axis, a second forming roll for each head, and a frame for rotatably supporting the second roll on each head, said frames
- being mounted to turn on axes extending transversely of their respective heads, and means mounted in each of the heads for 65 swinging said frames.
25. A machine of the character described comprising, in combination, a pair of forming rolls mounted to turn on fixed alined axes in spaced relation, and a second pair 70 of forming rolls respectively mounted for movement into and out of operative relation with the two first mentioned forming rolls, said forming rolls being shaped to form corrugations in opposite ends of a piece of 75 work entered therebetween, and the rolls at opposite ends of the work being mounted so as to permit a limited relative longitudinal movement during the forming operation.
26. A machine for corrugating one end portion of a metallic drum comprising, in combination, a pair of forming rolls of substantial length and mounted for relative movement from a substantially parallel relation into a position in which the axes of the rolls are approximately at right angles to each other with one of the rolls positioned wholly to one side of the other roll, and power-driven means for effecting such relative movement between the two sets of rolls.
27. A machine for corrugating the opposite end portions of a metallic drum having, in combination, two sets of forming rolls, means for supporting the rolls of each 95 set for relative movement from a position in substantially parallel relation to a position at approximately right angles to each other, the arrangement being such that when the two sets of rolls are in the last mentioned relation the drum may be moved transversely of the rolls into operative position relative thereto into a position to be operated upon, means for rotating one roll of each set only, and means for effecting 100 such relative movements between the two sets of rolls.
28. A machine for corrugating one end portion of a metallic drum comprising, in combination, a forming roll mounted to turn on a fixed axis, a second forming roll mounted for swinging movement from a position substantially parallel to the stationary roll into a position approximately at right angles to the axis of the stationary roll and to one side of the latter, a driven shaft mounted on an axis extending transversely of the axis of the stationary roll, and cam means on said shaft for swinging the movable roll.
- 115 In testimony whereof, I have hereunto affixed my signature.

CARL C. GROTNES.
